ALFRED J. WOOD, OF BROOKLYN, NEW YORK, ASSIGNOR TO UNDERWOOD COMPUTING MACHINE COMPANY, OF NEW YORK, N. Y., A CORPORATION OF NEW YORK.

COMBINED TYPE-WRITING AND COMPUTING MACHINE.

1,299,646.

Specification of Letters Patent.

Patented Apr. 8, 1919.

Application filed May 27, 1916. Serial No. 100,179

To all whom it may concern:

Be it known that I, ALFRED J. WOOD, a citizen of the United States, residing in Brooklyn borough, in the county of Kings, 5 city and State of New York, have invented certain new and useful Improvements in Combined Type-Writing and Computing Machines, of which the following is a specification.

10 This invention relates to power-transmitting mechanism which may form part of a combined typewriting and computing machine of the type in which a motor is intermittently connected to the mechanism to be 15 driven thereby.

The invention is in the nature of an improvement on the invention disclosed in the co-pending application Serial No. 875,554, filed Dec. 5, 1914, (now Patent No. 1,231,108, 20 dated June 26, 1917,) wherein there is shown an Underwood-Hanson typewriting and adding machine of the type in which the numeral keys of the typewriter are caused to set up pins which are subsequently engaged 25 by a general operator, which operates through suitable mechanism to rotate the dial wheels and run up the number corresponding to the actuated keys. Said application shows an electric motor which normally 30 remains at rest, except when driving the general operator, and which is controlled by a starting key. The latter controls a clutch for engaging the motor to drive the general operator and also controls a switch in the motor 35 circuit, so that when the starting key is depressed, the clutch and switch are closed, and the motor started, so that the general operator is driven through one complete operation, the clutch and switch being then 40 opened automatically to bring the parts to rest.

The present invention relates particularly to an improved form of clutch mechanism and switch, and means for controlling the 45 same.

In practising this invention the clutch is arranged to intermittently connect a driving element and a driven element, which may consist respectively of a gear connected to 50 be driven by the motor, and a shaft on which said gear is loosely mounted; said shaft being operable by one complete rota-

tion to effect an operation of the general operator of the computing mechanism. Said shaft may also operate suitable mechanism 55 for returning the typewriter carriage as shown in said co-pending application, into position to commence a new line of writing. The clutch may comprise a ratchet connected to said driving gear and pawls driven 60 thereby, said pawls mounted on a support connected to the said driven shaft. The clutch and switch controlling element may consist of a member mounted on the said driven shaft and having a limited rotation 65 relative thereto for controlling the clutch and also controlling a switch in the motor circuit. Said controlling element may be under spring tension and normally restrained 70 by a trip or stop pin, which may be withdrawn by the starting key, thereby permitting said controlling element to shift into position to effect a connection of the clutch parts, and concomitantly release a spring arm of the switch, permitting the switch to 75 be closed and the motor to start. As the driven shaft completes a rotation, said controlling member which rotates with it, is intercepted by the trip pin which, in the meantime had been restored, thus effecting a 80 movement of the controlling member relative to the shaft to release the clutch parts and open the switch.

A feature of the invention consists in the use of an electric switch, in which the switch 85 contacts have a relatively fixed mounting, so that they are stationary during the rotation of the clutch with which they are associated, the switch being mounted in the upper part 90 of the clutch casing, where it is protected from the accumulation of dust and dirt to which the usual rotating switch element is ordinarily subjected.

Other features and advantages will hereinafter appear. 95

In the accompanying drawings.

Figure 1 is a side elevation partly in section of a combined typewriting and computing machine, showing only such parts as are thought necessary to arrive at an understanding of my invention. 100

Fig. 2 is a fragmentary sectional front elevation of an enlarged scale taken on the line 2-2 in Fig. 1.

Fig. 3 is an elevation showing the clutch mechanism and switch, the pawls being out of engagement with the ratchet wheel, this being the normal position of the parts while the motor is at rest.

Fig. 4 is a similar view, but with the trip pin raised by the starting key and the parts moved to connect the pawls with the ratchet wheel and the switch closed.

Fig. 5 is a plan view of Fig. 3 and shows the relation between the contact springs before the starting key is actuated, some of the parts being shown in section.

Fig. 6 is a plan view of Fig. 4 and shows the contact springs closed and the parts in a position assumed after the starting key has been actuated.

Fig. 7 is a perspective view of the clutch mechanism and the switch with some of the parts separated from each other.

Fig. 8 is a circuit diagram showing the switch for closing the circuit from a source of power to a shunt motor.

Referring to Fig. 1, numeral key 9 and alphabet keys 10 when depressed, rock bell cranks 11 to swing type-bars 12 and cause them to print against a cylindrical platen 13 mounted on a carriage 14. The carriage is provided with a rack 15 which meshes with a pinion 16 to rotate an escapement wheel 17 when the escapement dogs 18 are reciprocated transversely thereof by a universal bar 19, said universal bar being moved by heels 20 on the type-bars when the latter are 25 swung to printing position. The carriage is moved from right to left by a spring drum 21 which is connected to the carriage by a strap 22.

In said combined typewriting and computing machine the numeral keys of the typewriter, set up numbers written in a certain column, by connections including a denominational dog or tappet 25 on the carriage, and other devices not shown in the drawings.

When a series of numbers has been set up, the operator depresses a starting key 26 to effect the operation of a general operator by which the set up numbers are carried into the 50 computing wheels (not shown), and at the same time causing the typewriter carriage to return to the proper point for starting a new line of writing.

The power for operating the general operator and for returning the carriage may be supplied by an electric motor 27 of the shunt type. The motor drives a shaft 28 connected to the motor shaft through a slip clutch 29 adapted to slip when the motor is subjected 55 to overload, such as might occur from jamming of the mechanism. When the shaft 28 is rotated, a worm 30 thereon drives a worm wheel 31.

The carriage is returned at the proper 60 time by the depression of the starting key 26

which moves a lever 32, causing the latter to rotate a second lever 33 about a pivot 34 to raise a clutch controlling trip pin 35. This causes the operation of clutch mechanism (hereinafter fully described) by which a driving connection is made from the worm wheel 31 to an operating shaft 36. At the same time a switch is operated (as fully explained later) to connect the motor 27 with a source of power so that the motor is started and rotates the shaft 36. A crank arm 37 at one end of the shaft 36 carries a crank pin 38 which engages with a block 39, the latter 70 slideable up and down in a groove 40 in a slide 41 and operating to drive the slide 41 75 forwardly. This latter structure may be identical with that shown in the patent to Frederick A. Hart, No. 1,190,233, dated July 4, 1916. The slide 41 has an extension 42 in engagement with a yoke 43 on a rack bar or 80 general operator 44, so that the latter moves forward with the slide. The forward movement of the rack bar 44 rotates a pinion 45 which meshes with a sector 46 to rotate the shaft 47. On the shaft 47 is a gear wheel 48 85 which rotates a pinion 49 to drive a drum 50 and wind up a strap 51 which passes over a guide roller 52 on the machine frame and is connected to the typewriter carriage so that the carriage is returned to start a new 90 line of writing.

The driving connection between the worm wheel or driving member 31 and the operating shaft or driven member 36 (Figs. 2, 3, and 7) is controlled by a clutch-operating 100 disk or movable element 55 (Fig. 7) which is mounted for a limited oscillating movement on a second disk 56. The disk 56 is fixed to the shaft 36 by a set screw 60. Shoulder screws 57 which pass through slots 58 in 105 the disk 55 and are threaded into holes 59 in the disk 56, permit the disk 55 to swing from the Fig. 3 position to the Fig. 4 position to clutch the wheel 31 to the shaft 36.

The worm wheel 31 is normally disconnected from the operating shaft by means of pins 63 on the disk 55 which hold pawls 61 out of engagement with a ratchet wheel 62. The pins 63 project through holes 64 in the disk 56 to engage with the pawls 61, the 115 pawls 61 being pivoted on headed studs 65 secured to the disk 56. The pawls are held against the pins 63 by springs 66 each anchored at one end to a pin 67 on the disk 56, and at its other end to a pin on the pawl. 120 As shown in Fig. 3, the clutch-operating disk 55 is held under tension by a spring 70 connected to one of the pins 67 and a bent-off portion 71 on the disk 55.

To connect the worm wheel 31 to the operating shaft 36, the trip pin 35 is raised, as heretofore described, by an actuation of the starting key 26, out of the path of the stop 125 lug 71. The parts will then move to the Fig. 4 position in which the disk 55 has been 130

slightly rotated by the spring 70 to move the pins 63 to allow the pawls 61 to be brought into engagement with the ratchet wheel 62 by means of the springs 66, thus effecting a one-way driving connection from the worm gear 31 to the shaft 36.

The switch which is normally open (Fig. 5) comprises contact spring arms 75, 76, provided with contacts 77 and mounted on a block of insulating material 78 by screws 79. The contact arms are connected to the motor by a pair of conductors 80. The block 78 is secured to the casing 81 by screws 82.

The switch is closed an instant after the worm wheel 31 is connected to the operating shaft 36. To accomplish this, there is mounted on the disk 55 and insulated therefrom, a finger 83 which normally engages with the spring arm 75 to hold it out of engagement with the contact arm 76. The arm 75 may be faced with a wear plate 75^a of steel or other suitable wearing material to prevent wear of the arm 75 by the finger 83. When the disk 55 is moved by the spring 70, the finger 83 is moved out of engagement with the spring arm 75 to permit the latter to engage with the spring arm 76 (Fig. 6), thus closing the circuit from the source of power to the motor 27. The motor instantly starts rotating to drive the operating shaft 36. It will be remembered that the shaft 28 is now connected to the operating shaft 36 by the worm 30 meshing with the worm wheel 31 which has rigidly connected thereto the ratchet wheel 62, connected to the disk 56 by pawls 61, the disk 56 being connected to the operating shaft 36 by the screw 60. The operating shaft 36 moves the general operator and through the train of gearing, heretofore described, returns the carriage to a position to start a new line of writing. The switch remains closed and the pawls remain in engagement with the ratchet wheel until the disk 55 has made a complete revolution when the bent-off portion 71 of the disk 55 engages with the trip pin 35 which has been returned to its normal position where it is in the path of said bent-off portion 71. As the disk 55 completes its rotation, the finger 83 opens the switch by moving the contact spring arm 75 away from the contact spring arm 76. The motor keeps rotating due to its inertia, and causes the limited movement of the disk 56 with relation to the disk 55 permitted by the slot-and-pin connections 58, 57, after the disk 55 has been arrested. This limited movement is effective to cause the disengagement of the pawls 61 from the ratchet wheel 62 by means of the pins 63.

It should be noted that the construction of the connecting mechanism and the switch is such that the pawls 61 are permitted to engage with the ratchet wheel 62 an instant before the switch is closed, so that the op-

erating shaft or driven member 36 is connected to the worm wheel or driving member 31 before the latter starts rotating.

It should also be understood that with the pawl and ratchet construction, the driving and driven members are readily connected and disconnected and that these operations and also the opening and closing of the switch are controlled from the disk or movable element 55. Also the disk or movable element 55 has a primary movement to effect a connection between the worm wheel or driving member 31 and the operating shaft or driven member 36, and a movement to close a switch. Said disk or movable element 55 has a reverse movement which is effective to open said switch, said disk being effective after the opening of the switch to disconnect the driven member from the driving member by means of the pins 63 engaging with pawls 61 which engage with the ratchet wheel 62.

It should further be understood that the contact springs are mounted at relatively fixed points and their contact points far removed from the lower part of the casing and thus protected from dirt which might accumulate in the bottom of the casing.

Variations may be resorted to within the scope of the invention, and portions of the improvements may be used without others.

Having thus described my invention, I claim:

1. The combination with a motor and mechanism to be driven thereby, of a rotary driving element and a rotary driven element connected respectively to the motor and said mechanism, a clutch comprising a pawl and ratchet mounted on said elements, a clutch controlling device mounted on the pawl-carrying element and having a limited shifting movement relatively thereto, by which the clutch pawl is controlled, means to shift said controlling device to cause the pawl to engage the ratchet and thereby cause the driven element to be rotated through a complete rotation, and means to shift said controlling device at the completion of a rotation of the driven element into position to release the pawl from its ratchet.

2. The combination with a motor and mechanism to be driven thereby, of a rotary driving element and a rotary driven element connected respectively to the motor and said mechanism, a clutch comprising a pawl and ratchet mounted on said elements, a clutch-controlling device mounted on the pawl-carrying element and having a limited shifting movement relatively thereto, by which the clutch pawl is controlled, means to shift said controlling device to cause the pawl to engage the ratchet and thereby cause the driven element to be rotated through a complete rotation, means to shift said controlling device at the completion of

130

- a rotation of the driven element into position to release the pawl from its ratchet, and a switch in the motor circuit comprising contacts held separated by said controlling device and released to close the motor circuit concomitantly with the connection of the clutch parts, said controlling device operable to cause the switch to open concomitantly with the separation of the clutch parts.
3. In a device of the class described, the combination with a driving member, of a driven member including a shaft on which said driving member is journaled, a fixed base adjacent said driven member, electric terminals on said base normally tending to close, a motor, a driving circuit for said motor including said terminals, a device on said driven member adapted to normally hold said circuit open through said terminals, a pin holding said device in its normal position, a spring normally tending to turn said device from its normal position to permit said terminal to close, a ratchet on said driving member, and pawls on said driven member normally held clear of said ratchet and forming a clutch between said members.
4. In a device of the class described, the combination with an electric motor, and a worm-driven driving member geared thereto, of a ratchet wheel fast to said driving member, a driven member including a shaft on which said driving member is journaled, pawls pivoted on said driven member, a controlling pin for each pawl, a disk on which said controlling pins are fast, a spring connecting said disk and said driven member tending to swing said disk to carry said pins to ineffective position, a starting pin normally holding said disk to keep said first-named pins effective, and a circuit for said motor normally open but closed by the withdrawal of said starting pin and held closed during the rotation of said driven member.
5. In a device of the class described, the combination with an electric motor and a worm-driven driving member geared thereto, of a ratchet wheel fast to said driving member, a driven member including a shaft on which said driving member is journaled, pawls pivoted on said driven member, a controlling pin for each pawl, a disk on which said controlling pins are fast, a spring connecting said disk and said driven member tending to swing said disk to carry said pins to ineffective position, a starting pin normally holding said disk to keep said first-named pins effective, a circuit for said motor including terminals mounted on a fixed base adjacent said disk, and an arm on said disk normally holding said circuit open through said terminals, the connections being such that movement of said disk upon withdrawal of said starting pin permits said circuit to

close and remain closed until said arm 65 again reaches the terminals.

6. In a device of the class described, the combination with an electric motor, of a driving member geared thereto, a driven member adapted to be driven by said driving member, a pawl-and-ratchet connection forming a clutch between said two members, a disk mounted on said driven member and adapted to rotate therewith, pins on said disk adapted to make said pawl ineffective, a spring joining said driven member to said disk tending to make said disk ineffective, thereby permitting the pawl to become effective, a starting pin normally holding said disk to keep the pawl ineffective, and an electric circuit for said motor held open by said disk when said starting pin is effective, said circuit adapted to be closed by the withdrawal of said starting pin, the connections being such that after the starting pin is returned to effective position, said circuit remains closed until the disk arrives at normal position when the circuit is opened and the arrest of the disk causes the pawls to free themselves from the ratchet and permits the motor to rotate idly.

7. In a device of the class described, the combination with a driven member comprising a shaft and a disk, of a driving member journaled on said shaft, a motor for driving said driving member, a pawl on said disk, a ratchet wheel on said driving member adapted to be engaged by said pawl to cause the driving member to turn the driven member therewith, a second disk journaled on said driven member, a pin on said second disk adapted to hold said pawl ineffective, a spring joining said second disk to said first disk adapted to hold the pin normally in ineffective position, a starting pin adapted to hold said second disk to keep its pin effective, an extension on said second disk, a circuit for said motor including fixed terminals adjacent said second disk, and an extension on one of said terminals adapted to be struck by said first extension to keep the circuit open when the second disk is held by the starting pin, and in all other positions of the second disk to hold said circuit closed.

8. In a device of the class described, the combination with a driving member and a driven member, of a shaft forming part of said driven member on which said driving member is journaled, a disk also forming part of said driven member, a pawl pivoted on said driven member, a ratchet on said driving member with which said pawl is adapted to coöperate to form a clutch between said members, a second disk having a limited motion on said first disk, a pin on said second disk adapted to hold said pawl ineffective at one position of the second disk, and permit said pawl to become effective at the other

position thereof, a spring tending to draw said second disk to position to permit said pawl to become effective, a motor driving said driving member, a circuit for said motor including terminals adjacent said second disk, an extension on one terminal, a starting pin adapted to hold said second disk to hold said pawl ineffective, an extension on said second disk adapted to engage said terminal extension to hold said terminal open when 10 the disks are at rest and the starting pin ineffective, and a spring normally tending to move said second disk to permit the pawl to become effective and the terminals to close.
